US0D1026131S

(12) **United States Design Patent** (10) **Patent No.:** **US D1,026,131 S**
(45) **Date of Patent:** **** May 7, 2024**

(54) **ROWING MACHINE**

(71) Applicant: **Shenzhen Yile Dynamic Technology Co., LTD**, Guangdong (CN)

(72) Inventors: **Jianfeng Lin**, Guangdong (CN); **Jinsong Fan**, Guangdong (CN)

(**) Term: **15 Years**

(21) Appl. No.: **29/860,110**

(22) Filed: **Nov. 16, 2022**

(51) **LOC (14) Cl.** 21-02

(52) **U.S. Cl.**

USPC **D21/674**

(57) **CLAIM**

The ornamental design for a rowing machine, as shown and described.

DESCRIPTION

FIG. 1 is a front and top perspective view of a rowing machine, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 1;

FIG. 10 is an enlarged perspective view of detail "10" identified in FIG. 1;

FIG. 11 is an enlarged perspective view of detail "11" identified in FIG. 2; and,

FIG. 12 is an enlarged perspective view of detail "12" identified in FIG. 2.

The dashed lines in the figures illustrate portions of the rowing machine that form no part of the claimed design. The dash-dot-dash lines in FIGS. 1, 2, and 9-12 illustrate the enlarged view indicators and also form no part of the claimed design.

1 Claim, 12 Drawing Sheets
